DESIGN FOR A CARPET SWEEPER CASING

Maurits de Kadt and Jacques de Kadt, New York, N. Y., assignors to Briam Industrial Corporation, New York, N. Y., a corporation of New York

Application November 22, 1946, Serial No. 134,996

Term of patent 14 years

(Cl. D9—2)

To all whom it may concern:

Be it known that we, Maurits de Kadt and Jacques de Kadt, subjects of the Queen of the Netherlands, residing at New York, in the county of New York and State of New York, have invented a new, original, and ornamental Design for Carpet Sweeper Casing, of which the following is a specification, reference being had to the accompanying drawing, forming part thereof.

Fig. 1 is a front elevational view of a carpet sweeper casing showing our new design;

Fig. 2 is a top plan view of the same, and

Fig. 3 is a side elevational view looking from the right in Figure 2.

We claim:

The ornamental design for a carpet sweeper casing, as shown,

MAURITS DE KADT.
JACQUES DE KADT.
